HAIR DRYER

Louis J. De La Marter, Lexington, Ohio, assignor to
Westinghouse Electric Corporation, a corporation of
Pennsylvania

Filed Mar. 16, 1964, Ser. No. 79,015

Term of patent 14 years

(Cl. D86—10)

Fig. 1.

Fig. 2.

Fig. 3.

Fig. 4.

Fig. 5.

FIGURE 1 is a top plan view of a hair dryer embodying my new design;

FIG. 2 is a front elevational view of the hair dryer of FIG. 1;

FIG. 3 is a side elevational view thereof;

FIG. 4 is a rear elevational view thereof; and

FIG. 5 is a bottom plan view thereof.

The side opposite that shown in FIG. 3 is a mirror image thereof.

The essential features of my design reside in the full line portions on the drawing.

I claim:

The ornamental design for a hair dryer, substantially as shown and described.
